UNITED STATES PATENT OFFICE.

ROLLAND THOMPSON, OF NEW YORK, N. Y.

CIGAR-HOLDER.

SPECIFICATION forming part of Letters Patent No. 678,444, dated July 16, 1901.

Application filed July 16, 1900. Serial No. 23,812. (No model.)

To all whom it may concern:

Be it known that I, ROLLAND THOMPSON, a citizen of the United States, and a resident of New York, in the county of New York and State of New York, have invented certain new and useful Improvements in Cigar-Holders, of which the following is a specification.

The object of this invention is to provide a cigar-holder so constructed that the cigar ¹⁰ can be rigidly secured therein and at the same time will prevent the binding so common to those forms of holders where the cigar-receiving end has a bell-mouth receiver; and it consists, preferably, in constructing the bowl ¹⁵ somewhat larger than the ordinary holder in the shape of a tapering tube which is provided with a centrally-apertured disk independent of the holder, so that the cigar is held within the holder by means of the said ²⁰ disk, and the small end of the cigar which passes into the bowl is therefore free of contact with the holder and cannot be pressed together within the bowl sufficiently tight to prevent easy smoking, all of which will now ²⁵ be set forth in detail.

In the accompanying drawings, Figure 1 is a longitudinal section of my improved cigar-holder, and Fig. 2 is an end view of the same. By the use of this holder it is impossible to ³⁰ insert the cigar so tightly as to prevent the free passage of air through the cigar, since the perforated disk is at a point on the cigar where the cross-section of the cigar is large enough to prevent compression to the extent ³⁵ necessary to prevent easy smoking.

The preferred form of constructing the invention is shown in the drawings, wherein the holder is made, preferably, of a tapering tube 11 of any desired length, open at both ends, within the larger end of which is placed ⁴⁰ a disk 12, with the central aperture 7 large enough to receive and hold the end of a cigar. This disk may be removable, so that in practice the disk or ring-like piece can be fitted to the end of a cigar and then placed in the end of ⁴⁵ the tube, or it may be cast in one piece with the same.

It is obvious that various mechanical forms may be constructed having in substance the essence of my invention without departing ⁵⁰ from its spirit, which is essentially to provide one end of a tubular cigar-holder with a centrally-perforated disk for holding the cigar.

What I claim as new is—

The combination with a cigar-holder consisting of a tapering tube and a mouthpiece, of a centrally-apertured disk adapted to be placed on the end of a cigar independent of the holder and be inserted within the said ⁶⁰ tube, substantially as set forth.

Signed at New York, in the county of New York and State of New York, this 15th day of May, A. D. 1900.

ROLLAND THOMPSON.
